(57) **CLAIM**

The ornamental design for a massage device, as shown and described.

DESCRIPTION

FIG. 1.1 is a front view of the massage device;

FIG. 1.2 is a right view thereof;

FIG. 1.3 is a back view thereof;

FIG. 1.4 is a perspective view thereof;

FIG. 1.5 is a top view thereof;

FIG. 1.6 is a bottom view thereof.

The broken lines in the reproductions disclose unclaimed subject matter only, and form no part of the claimed design. The left view is a mirror image of the right view, and it is not shown.

1 Claim, 6 Drawing Sheets(56)
